LINE CONTROL FOR CAN MAKING MACHINES

William H. Meyer, Chicago, Ill., assignor to Continental Can Company, Inc., New York, N. Y., a corporation of New York

Application April 25, 1932. Serial No. 607,475

3 Claims. (Cl. 198—26)

This invention relates to new and useful improvements in a line control for a can making machine, and more particularly to a control mechanism for the cans which are fed to a tester. It is a common practice to provide a tester having a series of testing units mounted for rotation about a common axis, and each testing unit has a pocket or support to receive the can which is to be tested. The cans are fed into these pockets one at a time as they travel past a delivering chute. It is essential that a pocket shall be in alignment with the chute upon the initial starting of a line of cans or otherwise the can is likely to catch between the side wall of the pocket and the frame resulting in a jam.

An object of the present invention is to provide a means for controlling the discharge of the foremost can into the pocket until the pocket is in alignment with the chute.

A further object of the invention is to provide a control mechanism for the cans being delivered to the can making machine, which automatically restrains the movements of the cans into the machine when the supply of cans on the line is insufficient to meet the demands of the machine.

A still further object of the invention is to provide a control mechanism for the cans of the above type wherein the feed of the cans to the machine is automatically resumed when there are sufficient cans to supply the demand of the machine.

These and other objects will in part be obvious and will in part be hereinafter more fully disclosed. In the drawings which show by way of illustration one embodiment of the invention—

Figure 1 is a side view showing more or less diagrammatically a portion of a tester wheel and several of the testing units and also the line discharging cans into the tester and the control mechanism therefor;

Fig. 2 is a front view showing more or less diagrammatically parts of a tester, and the means for controlling the delivery of the cans into the same;

Fig. 3 is a view partly in section and partly in side elevation of a portion of the tester wheel from the opposite side as viewed in Fig. 1;

Fig. 4 is a view partly in section and partly in plan showing the control mechanism for controlling the movements of the cans with the control finger retracted;

Fig. 5 is a plan view of a portion of the mechanism shown in Fig. 4, with the control finger in position for restraining the movements of the cans;

Fig. 6 is a view of the control mechanism taken on the line 6, 6 of Fig. 4;

Fig. 7 is an enlarged view of the control out on a line for restraining the delivery of cans to the machine when the supply diminishes so as to be insufficient so as to completely supply the demand of the machine;

Fig. 8 is a vertical sectional view through the can runway and showing the control mechanism in side elevation;

Fig. 9 is a plan view of the mechanism shown in Fig. 7, and

Fig. 10 is a view showing the position of the control bell crank when the cans are forced past the stop arms.

The invention has to do with a line control for cans which are being fed to a can machine, and more particularly to a tester. The tester includes a series of units, each of which is provided with a pocket to receive the can and center it between the clamping devices which closes the can preparatory to the testing of the same for a leak. The tester wheel carrying the testing units rotates continuously and the cans are fed one at a time on to a support associated with each unit. The cans are delivered to the machine from a runway of the usual type. Adjacent the tester wheel is a control device in the form of a finger which is moved forward into the open end of the can for restraining the movements of the cans. This control finger is in part electrically controlled and in part mechanically controlled. Out on the line is a control switch which closes the circuit when the supply of cans on the line ceases in the region of the switch, and when the circuit is established through a solenoid at the tester wheel, the control finger is released so that it moves forward to stop the flow of cans. When the switch is closed, the solenoid is de-energized. The control finger, however, is mechanically held retracted and is released by a member carried by the tester wheel, so that the can bodies will be released for discharge into the wheel only when the pocket or support of the tester unit is in alignment with the conveyor.

There is on the line associated with the switch which stops the flow of cans, a control device which insures that the switch will remain closed and the finger held in position for restraining the movements of the cans until sufficient cans accumulate on the line to supply the normal demand of the machine.

Referring more in detail to the drawings, in Fig. 1 there is shown diagrammatically a portion of a tester wheel which is indicated at 1. This

wheel is mounted for rotation about an axis 2. Mounted on the wheel is a series of tester units indicated at 3, 3. Each tester unit includes a support 4 on which the can rests preparatory to 5 clamping the same against the pad 5 by the movement of a plate 6 which engages the bottom of the can. This forces the open end of the can against the pad, thus closing the can, after which it is tested for a leak. The mechanism 10 of the tester is of the usual character and forms no part of the present invention. The plate 6 and the support 4 are carried by a rod 7 which is mounted for endwise reciprocation in the frame of the wheel. A link 8 is connected at its outer 15 end to a pin 9 mounted on the rod, and at its inner end to a pin 10 carried by the arm 11 which is attached to the shaft 12. Also mounted on the shaft 12 is an arm 13 carrying a roller 14. The roller 14 passes between two cam-shaped guide plates 15, 15 attached to the frame which swings the arm 13 to the position shown in Fig. 2. In this position the arm 11 and link 8 are substantially in alinement, and the rod 7 has been moved endwise so as to clamp the can against a pad 20 for testing. This movement of the rod 8 is so timed that the parts are not moved until a can is placed on the support 4. The cans are indicated in the drawings at C. The cans travel along a horizontal runway of the usual type 25 which is indicated at 16. They are moved along the runway by a cable 17. They are passed by the cable into a vertical runway 18 and are fed by gravity into a runway 19 which leads to the tester wheel. The axis of the can is substantially horizontal as it passes into the tester wheel. The pivoted arm 20 carrying the flexible member 21 bears on the cans after they pass into the wheel and aids in holding the can properly seated on the support while it is being clamped. Adjacent the tester wheel is a control finger 22 carried by a rod 23 mounted for endwise movement in supporting brackets 24 and 25. On the end of the rod is a head 26 in which the control finger 22 is clamped. As clearly shown in Figures 4 and 5, the open end of the can faces the finger, and when the rod 23 is moved to the right from the position shown in Fig. 4 to the position shown in Fig. 5, the finger is moved into the can and will restrain the movement of the can along the runway. This stops the flow of cans along the runway. The finger is moved into the can for restraining the flow of the cans by the solenoid 27, the core 28 of which is pivotally connected to a bell crank lever 29 mounted on a bracket 30. The bell crank lever at its upper end is connected to a collar 31 fixed to the rod 23. A weight 32 is attached to the lower end of the core 28. When the solenoid is energized, the core 28 is raised, and this will move the rod 23 to the right to the dotted line position in Fig. 2, and the full line position in Fig. 5. Thus the flow of cans into the machine is stopped. Associated with the runway 16 is a control switch which includes an arm 33. This arm is attached 60 to a shaft which also carries a weight 34 normally pressing the arm upwardly. The upward movement of the arm is restrained by the cans C passing along the runway. If the supply of cans gives out, then the arm 33 will swing into the 65 path of travel of the cans and this will close the switch in the switch box 35. Closing the switch in the switch box 35 energizes the solenoid 27 and shifts the control finger so as to stop the movement of the cans into the tester 70 wheel. When the supply of cans on the runway 75

16 is resumed, the arm 33 is depressed by the engagement of the cans therewith, and this will open the circuit and de-energize the solenoid. In order that the control finger will still be held in position to prevent the movement of the cans into the tester wheel until a pocket or support is in proper position to receive the can, a mechanical latch is provided which holds the control finger in its forward position. Mounted on the shaft 36 is an arm 37 which when moved upwardly, engages the rod 23. The shaft 36 also carries an arm 38. Attached to the arm 38 is an adjustable head 39 carrying a finger 40. A spring 41 is attached at one end to the arm 38 and at its other to the supporting bracket 42 for the shaft 36. This spring normally moves the arm 38 downwardly thus raising the arm 37. When the control finger is retracted, the arm 37 contacts with a collar 43 adjustably mounted thereon. When the control finger is moved to the right to the position shown in Fig. 5, then the arm 37 engages the rod 23, and movement of the rod to the left is restrained by the arm 37. The finger 40 normally overlies the path of travel of the links 8 when the arm 37 is raised. Upon the energizing of the solenoid, the rod 23 is moved to the position shown in Fig. 5, and the arm 37 will contact with the rod, so that when the solenoid is de-energized, the collar 43 engages the arm and restrains the movements of the finger. This lowers the arm 38 and places the finger 40 in the path of travel of the link 8 of the approaching testing unit. The link 8 will, therefore, strike the arm 40, thereby swinging the arm 37 downward and release the rod 23 so that the weight 32 will retract the same. 100

From the above it will be apparent that a control means has been provided which stops the flow of cans when the supply on the runway diminishes and is insufficient to meet the normal demand of the testing machine. As soon as the supply is resumed, the solenoid is released, but the control finger remains in its forward position restricting the flow of cans until a mechanical latch is tripped and this allows the cans to 115 flow forward, but only at the time when the pocket or support of the testing unit is in alinement with the delivery chute. 120

After the flow of cans has been stopped, it is desirable that the feed of the cans should not 125 be resumed until there are sufficient cans on the line to supply the normal demand of the machine. In other words, it is not desirable to release the cans when only one or two cans on the line pass the switch arm, unless there are other 130 cans to follow to be fed to the machine. The line is, therefore, provided with a device for controlling the forward movement of the cans until a considerable number accumulate on the line. This control device includes two arms 44, 44 attached to the head 45 of a lever 46. The lever 46 is pivoted at 47 in a bracket 48 attached to the side of the runway. There is an arm 49 formed as an extension of the lever 46. This arm 49 extends through an elongated opening 50 in an arm 51 of a rock lever which is pivoted at 52. The other arm 53 of the rock lever has an opening therethrough to receive the core 54 of a solenoid 55. This core 54 is provided with a fixed collar 56, and at the lower end of the collar is a 140 nut 57 carrying a washer 58 which serves as an abutment for a spring 59. When the solenoid 55 is energized, the lever is oscillated and will move the arms 44 into the runway so as to stop the 145 flow of cans. The cans may be stopped and the 150

cable will slip underneath the cans. The solenoid 55 is in multiple with the solenoid 27 so that when the arm 33 is raised, the solenoid 55 will be energized and will move these arms 44 into a position for stopping the flow of cans. As the cans accumulate on the line, the pressure against the arms is greatly increased and will finally reach a force so as to compel the arms to move out of the path of travel of the cans. At this time the spring 59 is compressed and allows the arms to move sufficiently to permit the cans to pass, although the solenoid 55 is still energized, and the core held in raised position. As the cans pass the ends of the arms 44, they will engage the arm 33, depressing the same, and this will break the circuit and de-energize the solenoid 55, which drops by its own weight.

In the operation of the control mechanism as a whole, the flow of the cans at the tester wheel is stopped when the supply of cans out on the line decreases sufficiently so as to permit the arm 33 to be raised. The arm 33 is only depressed for re-establishing the flow of cans into the machine after sufficient cans have accumulated on the line to supply the normal demand of the machine for a time at least. When the supply is sufficient to pass the arms 44 and open the switch by depressing the arm 33, thus de-energizing the solenoid at the tester wheel, still the control finger is not released until the mechanical latch is tripped, and this occurs when the pocket of the tester unit is in proper alignment with the delivery chute to receive the can.

While the invention has been described specifically as applied to the control of cans flowing into a tester machine, it will be understood that it may be used in connection with other machines where it is desired to time the cans into the machine when the flow of cans to the machine is initiated. After the flow of cans has been properly initiated, the pockets are so spaced from each other that the cans control their own alignment. That is to say, if the can passing from the delivery chute is properly timed into one pocket of a testing unit, the next following can will be properly timed into the succeeding testing unit.

It is obvious that minor changes in the details of construction and the arrangement of the parts may be made without departing from the spirit of the invention as set forth in the appended claims.

Having thus described the invention, what I claim as new and desire to secure by Letters-Patent, is—

55 1. The combination of a can machine having a series of traveling operating units, a discharge chute for delivering cans one at a time to the passing units and mechanism for controlling the movement of the cans in the discharge chute including a control finger, a solenoid, means controlled by the solenoid and connected to said finger so that when said solenoid is energized the finger will be moved into the path of travel of

the cans, means for retracting the finger when the solenoid is de-energized, a latch, yielding means for moving the latch so as to hold the control finger in a position for engagement with the cans and means carried by a traveling part of the machine and associated with each operating unit for releasing the latch in proper time for discharging the advance cans into a passing operating unit.

80 2. The combination of a can machine having a series of traveling operating units, a discharge chute for delivering cans one at a time to the passing units, and mechanism for controlling the movement of the cans in the discharge chute including a control finger, a solenoid connected thereto for moving the finger into the path of the cans when energized, independent means for retracting the finger, mechanical means operated by a moving part in the can machine for restraining the movement of the control finger when released by the solenoid and for releasing said finger at a predetermined time for discharging the advance can into a passing operating unit, a switch on the line at a point distant from the machine having an arm yieldingly moved into the path of travel of the cans for closing the switch, said switch being connected in circuit with the solenoid, whereby when the cans give out on the line, the switch will be closed and the solenoid energized, arms on the line for restraining the movement of the cans on to the switch arm, a solenoid connected to said arms for moving the arms into the path of travel of the cans when energized, said solenoid being connected

85 90 95 100 105 110 115 120 125 130 135 140 145 150

when the switch is closed, the arms move into the path of the cans, and yielding means for connecting said last-named solenoid with the arms whereby when the cans accumulate on the line in sufficient number, the cans will be forced past said arms into engagement with the switch arm, opening the switch and breaking the circuit for both solenoids.

3. The combination of a can machine having a series of traveling operating units, a discharge chute for delivering cans one at a time to the passing units, and mechanism for controlling the movement of the cans in the discharge chute including a control finger, a solenoid, a rock shaft attached to the solenoid, said rock shaft being connected to said control finger, and disposed so that when said solenoid is energized, the finger will be moved into the path of travel of the can, means for retracting the finger when the solenoid is de-energized, a latch, yielding means for moving said latch so as to hold the control finger in a position for engagement with the cans, and means carried by a traveling part of the machine and associated with each operating unit for releasing the latch in proper time for discharging the advance can into a passing operating unit.

WILLIAM H. MEYER.
